(57) **CLAIM**

The ornamental design for a portable sauna tent, as shown and described.

DESCRIPTION

FIG. 1 is a front, right, top perspective view of a portable sauna tent, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is a front, right, top perspective view of the reduced scale in an alternate configuration; and,

FIG. 11 is a rear, left, bottom perspective view of the reduced scale in an alternate configuration.

The dashed broken lines in the figures are for the purposes of illustrating portions of the portable sauna tent and form no part of the claimed design.

The dot-dash broken lines in FIGS. 1 and 9 represent boundaries of the enlarged portions and form no part of the claimed design.

1 Claim, 11 Drawing Sheets
